US00D813166S

(12) **United States Design Patent** (10) **Patent No.:** **US D813,166 S**
(45) **Date of Patent:** **** Mar. 20, 2018**

(54) **TRANSCEIVER**

(71) Applicant: **Shenzhen City Tongsheng Electronic Technology Co., Ltd.**, Shenzhen, Guangdong (CN)

(72) Inventor: **Hailiang Huang**, Guangdong (CN)

(73) Assignee: **Shenzhen City Tongsheng Electronic Technology Co., Ltd.**, Shenzhen (CN)

(**) Term: **15 Years**

(21) Appl. No.: **29/572,012**

(22) Filed: **Jul. 25, 2016**

(51) LOC (11) Cl. **13-03**

(52) U.S. Cl.

USPC **D13/123**

(57) **CLAIM**

The ornamental design for a transceiver, as shown and described.

DESCRIPTION

FIG. 1 is a front elevation of the transceiver showing our new design;

FIG. 2 is a back elevation view thereof;

FIG. 3 is a left elevation view thereof;

FIG. 4 is a right elevation view thereof;

FIG. 5 is a top view thereof;

FIG. 6 is a bottom view thereof; and,

FIG. 7 is a perspective view thereof.
